HAND-OPENING SHEET METAL END CLOSURE
William T. Saunders, Weirton, W. Va., assignor to National Steel Corporation, a corporation of Delaware
Filed Dec. 6, 1966, Ser. No. 599,442
1 Claim. (Cl. 220—54)

ABSTRACT OF THE DISCLOSURE

An improved hand-openable metal end closure in which an elongated tab opener is secured to the end closure to provide class 1 lever action for puncture of the end closure along a preformed scoreline. The tab opener has a wedge-shaped configuration at its puncturing end. Portions of the tab opener forming the wedge-shaped configuration cross the scoreline and prevent puncturing beyond a desired limit and spread sheet metal along the scoreline to make possible removal of the punctured portion of sheet metal from the remainder of the end closure without binding along the scoreline.

This invention is concerned with an improvement of hand-openable, sheet metal end closures for containers.

More specifically, this invention is concerned with improvement of hand openers which rely on class 1 type lever action as described in applicant's co-pending application S.N. 495,796, entitled, "Container Structure and Manufacture," filed Oct. 14, 1965. With this type of hand opener a securing means, such as a rivet, is used for securing a tab (handle) to a sheet metal end closure. The rivet acts as a fulcrum for a class 1 lever which initiates puncture of the end closure. While this structure provides easy hand operation, it has been found that, with the high mechanical advantage available for puncturing a sheet metal end closure because of applicant's earlier invention, a greater portion of the sheet metal to be removed from the end closure is forced downwardly below the level of the remaining portion of the sheet metal in the end closure than is desired. When this portion of sheet metal is pulled backwardly to complete opening of the container, it binds with the periphery of the puncture formed in the end closure and, for an instant, impedes completion of opening.

The contribution made by the present invention acts to spread sheet metal at the periphery of the end closure puncture to overcome any possibility of binding and sets definite limits on the puncture formed which stabilizes positioning of the fulcrum.

In describing a specific embodiment reference will be had to the accompanying drawings wherein:

FIGURE 1 is a portion of a hand-openable end closure with its tab opener located within a scoreline as described in applicant's earlier patent application referred to above.

FIGURE 2 shows the hand opener of FIGURE 1 in a partially open position after puncture of the end closure.

FIGURE 3 is a portion of a hand openable end closure embodying the invention.

FIGURE 4 shows the embodiment of FIGURE 3 in a partially open position after puncture of the end closure, and

FIGURE 5 is an enlarged showing of a portion of the structure of FIGURES 3 and 4.

Referring to FIGURE 1, rivet 10 secures tab opener 12 to a scored portion 14 defined by scoreline 16 on a sheet metal end closure. It should be noted that tab opener 12 is located entirely within the scoreline 16 so that a perpendicular projection of tab opener 12 on scored por-

2

tion 14 falls entirely within scoreline 16. While this has a number of advantages as set forth in applicant's earlier mentioned patent application, it also has a number of disadvantages related to binding of sheet metal along the scoreline after puncture which will be discussed in relation to FIGURE 2.

Referring to FIGURE 2, which shows the structure of FIGURE 1 after puncture of the end closure, it will be seen that the class 1 lever action resulting from lifting of end 20 of tab 12 causes puncturing end 22 of lever 12 to penetrate into the container. It has been found that because of the mechanical advantage provided by this lever action, puncturing end 22 penetrates the container more than desired, e.g., beyond rivet 10, causing bending of the scored portion 14 along dotted line 24.

In order to complete removal of the scored portion 14, tab opener 12 must be pulled backwardly in a direction opposite to that of the puncture. When attempting to remove the punctured portion of the scored sheet metal it has been found that binding occurs at points 26 and 28, such that easy removal is impeded. The present invention which will be described in relation to FIGURES 3 through 5 overcomes these disadvantages of the type of hand opener shown in FIGURES 1 and 2.

Referring to FIGURE 3, elongated tab opener 30 is secured to a scored portion 32 of an end closure by rivet 34. Tab opener 30 includes a narrow-width curvilinear edge 36 and an opposite longitudinal end 38 which has a substantially wider configuration.

The narrow-width curvilinear edge 36 increases in width along legs 39 and 40 to present a wedge-shaped configuration with the wedge opening toward longitudinal end 38.

Referring to FIGURE 4, the class 1 lever action produced by lifting on end 38 causes narrow-width end 36 to break sheet metal along the curved configuration scoreline portion 42. However, legs 39 and 40 of the wedge-shaped configuration of the tab opener cross the scoreline at points 44 and 46 and supplement the fulcrum action of rivet means 34, that is legs 39 and 40 act to stabilize the position of the fulcrum of the class 1 lever along the longitudinal axis of the tab opener 30. Further, legs 39 and 40, in crossing of the scoreline, spread metal at the periphery of the puncture and prevent penetration of end 36 to the extent shown in applicant's earlier embodiment shown in FIGURE 2.

As shown in FIGURE 5, legs 39 and 40 crossing the scoreline at points 44 and 46 cause sheet metal along the scoreline to bulge outwardly, that is away from the opening, at these points. Therefore, upon pulling back tab opener 30 to complete opening of the container there is no binding of the sheet metal which has penetrated below the surface of the remainder of the sheet metal blank with metal along the periphery of the puncture. Absence of binding makes possible the complete removal of the scored portion of the end closure in a smooth succession of steps.

While the embodiment shown depicts a ring-pull tab opener and a pour-opening scoreline, it is understood that the invention is not limited to these embodiments since a tab opener of other configurations, such as a generally rectangular configuration with the wedge-shaped configuration can be used with either a pour-opening end closure and the scoreline configuration can extend around the circumference of the end closure to provide a full-open end closure. Also the teachings of the invention are applicable to any of the conventional sheet metals used for making metallic end closures.

What is claimed is:

1. Hand-openable sheet metal end closure for a container comprising

a sheet metal blank,
 an elongated tab opener means having a narrow-width longitudinal end and a remaining longitudinal end, the narrow-width end having a curvilinear edge configuration from which the width of the tab opener means increases to define a wedge-shaped configuration opening in the direction of the remaining longitudinal end of the tab opener means, 5
 a scoreline of diminished metal thickness in the sheet metal blank defining an area to be removed by the tab opener means, the scoreline having a curvilinear portion for initiating removal of the area defined by the scoreline from the sheet metal blank, and
 means for securing the tab opener means to the scored area of the sheet metal blank, such means being located within the area defined by the scoreline contiguous to the curvilinear portion for initiating removal of the area defined by the scoreline, so that a perpendicular projection of the curvilinear edge of the narrow width longitudinal end of the tab opener means lies within and substantially parallel to the contiguous curvilinear configuration portion of the scoreline and such that a perpendicular projection of the wedge-shaped configuration portion of the tab opener means crosses the scoreline adjacent to and 10
 on opposite sides of the means for securing the tab 15
 20
 25

opener means to the scored area of the sheet metal blank, the tab opener means being thus secured to the sheet metal blank so as to constitute a class 1 lever with the means for securing the tab opener means acting as a fulcrum so that the curvilinear edge narrow-width longitudinal end of the tab opener means punctures the sheet metal blank and forces a portion of the scored area of the sheet metal downwardly below the remainder of the sheet metal blank by a lifting action at the remaining longitudinal end of the tab opener means, with the wedge-shaped portion of the tab opener means acting to spread sheet metal along the scoreline of the sheet metal blank for easy removal of sheet metal extending downwardly below the remainder of the sheet metal blank.
